UNITED STATES PATENT OFFICE.

JOHN H. LYNCH, OF NEW YORK, N. Y., ASSIGNOR TO THE MERGENTHALER LINOTYPE COMPANY, OF NEW YORK.

LINOTYPE-MACHINE.

SPECIFICATION forming part of Letters Patent No. 657,429, dated September 4, 1900.

Application filed March 31, 1900. Serial No. 10,932. (No model.)

To all whom it may concern:

Be it known that I, JOHN H. LYNCH, of New York, county of New York, and State of New York, have invented a new and useful Improvement in Linotype-Machines, of which the following is a specification.

My invention relates to improvements in the mechanism for delivering type or type-matrices one at a time from a magazine or holder and assembling them in line in the required order.

Many machines are known in the art in which type and type-matrices (which as regards the purposes of this invention are to be considered as equivalents) are released one at a time from the respective channels or grooves of a magazine, the releasing devices being actuated or set in motion by finger-keys or equivalent controlling devices.

One of the chief difficulties encountered in the operation of these machines at high speed lies in the transposition of the characters, due to the fact that the type are released from the magazine at varying distances from the point of assemblage, so that the time required for the passage of certain type from the point of release to the composed line is much greater than that required for the passage of other type. Many mechanisms have been devised

to overcome this difficulty, the plan generally employed being that of using a carrier-belt lying at an angle to the mouth of the magazine, so that type which have the greatest distance to travel are received on the belt

immediately upon being released, while the type which would otherwise have a less distance to travel are required to move a considerable distance after leaving the magazine before they reach the carrier-belt. Now this oblique arrangement of the carrier-belt is attended necessarily by other peculiarities of construction in the machine which are open to objection.

Now the object of my invention is to overcome these difficulties and provide an assembling mechanism in which the type may be carried in very rapid succession to the line without danger of transposition and without the employment of the obliquely-arranged carrier. To this end it consists in a power-

driven mechanism in which the escapement or releasing devices start at a longer or a shorter interval after the actuation of the finger-key, according to the distance of the escapement from the point of assemblage. In other words, in my mechanism an escapement or discharging device remote from the point of assemblage starts instantly upon the touching of the finger-key by which it is controlled, while on the other hand an escapement located nearer the point of assemblage does not begin its action until a predetermined time has elapsed after the action of its controlling-key. The time which elapses between the actuation of a key and the movement of the corresponding escapement increases from key to key as the point of assemblage is approached. In consequence of this arrangement a key near the assembling-point may be operated quickly after a key at a remote point; but the action of the second escapement will be delayed sufficiently to permit the type released by the first key to reach the line in advance of the type released by the second key, although the letter may be much nearer the assembling-point; or, to state the matter differently, the fingering of the keyboard is followed by the release of each type a little more quickly than the release of the type next nearer the point of assemblage. Consequently it is possible for the operator to manipulate the keyboard at high speed and without considering in any manner the distance which the respective type have to travel and without danger of transposing them in the line.

For the purposes of illustration I have shown my invention as incorporated in a linotype keyboard mechanism of the general character represented in Letters Patent to P. T. Dodge, No. 530,931, dated December 18, 1894.

Figure 1 represents a front elevation of the magazine, assembling-belt, and keyboard. Fig. 2 is a side view of the same, portions of the keyboard being shown in vertical section. Fig. 3 is a top plan view of one end of the keyboard mechanism with portions broken away. Fig. 4 is a perspective view illustrating a keyboard-roll and three of the cams so positioned as to start in varying times. Fig. 100

5 is a view showing an alternative or equivalent construction.

Referring to the drawings, 1 represents an ordinary inclined magazine of a Mergenthaler machine grooved internally to guide the matrices 2, which descend therethrough by gravity, escaping when released at the front through the vertical guides 3 to the carrier-belt 4, the upper surface of which lies in a horizontal position and parallel with the mouth of the magazine, so that all of the matrices on being released travel an equal distance to reach the carrier-belt. The belt being driven in the direction indicated by the arrows delivers the matrices one after another into the assembling-elevator, in which they are assembled or composed in line, as usual.

The escapement of the matrices from the magazine-channels is effected by the oscillating escapements 7, which are in turn actuated by the vertically-guided rods 6, each drawn downward by a spring 39, as usual. The lower ends of these rods stand each over the free end of a vertically-swinging yoke 27, mounted on the horizontal pivot 28 and slotted vertically to receive a cam 23, turning on a horizontal pin therein. There is a series of the yokes, one for each key-rod 6, the yokes of the successive rods being arranged alternately to the right and left of the central line for the purpose of convenience and compactness of arrangement. 21 and 22 represent two continuously-revolving rubber-covered rolls extending horizontally under the respective rows of cams 23, so that each cam stands directly over the roll, but normally out of contact therewith. Each yoke has its free end supported normally in an elevated position by an underlying angular dog 29, mounted on a fixed pivot 30, and engaged at its lower forward end by a finger-key lever 32, the parts so arranged that when a key-lever is operated the dog 29 will release the yoke 27 and permit it to fall until its cam rests upon the underlying roll in order to be turned by frictional engagement therewith. While the yoke is in its normal position its cam 23 is prevented from rotating by a stop-shoulder 23' therein engaging a rigid stop-pin 24, depending from the frame. The cam is weighted on one side, so that its stop-shoulder remains in contact with the stop-pin, whereby the cam is prevented from turning backward accidentally. When a finger-key is actuated and the yoke 27 released, it falls, so that its cam is carried out of engagement with the stop-pin above at the same time its frictional engagement occurs with the roller below. The rotation of the roll by turning the cam causes the latter to lift the yoke 27 not only to its original level, but to a still higher level, so that its free end acting upon the overlying rod 6 causes the latter to actuate the escapement 7, thereby delivering a matrix from the magazine. While this action is taking place the dog 29 again assumes its position under the cam-yoke, so that the latter in falling is arrested

in its original position in order to hold its cam 23, which has made one revolution, out of engagement with the roll and in engagement with the stop-pin above. The foregoing action occurs as to all the finger-keys and escapements, which is essentially the same as the action of the parts in the Dodge patent above referred to, except as to the feature of invention, which I will now describe. In the Dodge patent the various cams in the row have their stop-shoulders in one and the same position and the stop-pins are arranged in a line parallel with the axes of the cams, so that the action of all the escapements is practically instantaneous when the corresponding keys are depressed. I arrange the stop-shoulders of the successive cams at different distances from the shoulders or high points on the periphery of the cams, so that the various cams are stopped and held at rest in different relations to the underlying rolls. The cams on the right of the keyboard (the end most remote from the point of assemblage) have their stop-shoulders so positioned that the cams are held with their elevated portion or portions of greatest diameter close to the underlying roll, so that when the parts are released the roll will take hold of and initiate the rotation of the cam instantly, causing the immediate action of the escapement. The successive cams moving toward the left of the keyboard have their stops positioned to hold their cam-shoulders each a little farther away from the roll than the shoulder of the next cam. Thus it is that the cams toward the left of the keyboard are compelled to turn farther, or, in other words, to make a greater portion of a revolution, than the cams to their right before their elevated surfaces reach the rubber rolls and before they begin to actuate the escapements. To illustrate a cam at the extreme right of the board will take hold of the roll and will begin to operate the escapement instantly, while a cam farther to the left may have to make an eighth of a revolution before beginning to actuate its escapement. One still farther to the left may require to make a quarter of a revolution before beginning to move its escapement, and so on successively. If all the keys in the board were depressed at one instant, the escapements of the machine would be operated in succession from right to left. In consequence of this arrangement a matrix released from any channel of the magazine will be given time to reach the carrying-belt and to travel toward the assembler so far that it will be in advance of any matrix released from the magazine at a point farther to the left, or, in other words, from a point nearer the point of assemblage. The general effect of the arrangement is, it will be observed, to equalize the time required for the passage of the matrices from the magazine to the composed line. When the parts are properly proportioned and speeded, it is practically impossible to operate the keys in such manner that a ma-

trix released from any part of the magazine will reach the line in advance of a matrix previously released.

Instead of the foregoing arrangement for operating the escapements in different times I may employ an arrangement such as shown in Fig. 5, involving the same principle. In this instance the cams are all made alike and arranged to stop in like relations to the underlying roll; but the roll is tapered or conical in form, with its larger end remote from the point of assemblage, so that the cams engaging the roll at different points in its length will be revolved at different rates of speed, the speed increasing with the successive cams from the left toward the right. When, therefore, a key at the right of the keyboard is actuated, its cam will be turned very rapidly and its escapement operated immediately, while a cam at the left of the keyboard on being released will turn at a comparatively low rate of speed, so that its escapement will not be actuated to release a matrix until the matrix released by the first escapement has passed on its way to the line.

The essence of the invention lies in the time-controlled keyboard so arranged that the matrices represented by different keys will be discharged at a longer or a shorter interval after the actuation of the key, according to the distance which the matrix is required to travel in passing to the line from the magazine.

It will be manifest to the skilled mechanic that the mechanism may be widely modified in detail without passing beyond the limits of my invention.

What I claim as my invention is—

1. In a composing mechanism, the com-

nation of type-discharging devices, corresponding finger-keys, and intermediate mechanism to vary the interval between the action of the respective keys and discharging devices, according to the time required for the type to pass from the respective discharging devices to the point of composition.

2. In a composing mechanism, a series of time-controlled type-discharging devices, graduated as to their relative speeds according to the time required for the travel of the respective type, substantially as described and shown.

3. In a composing mechanism, the combination of a continuously-revolving roll, a series of type-discharging mechanisms adapted to be thrown independently into engagement therewith, said parts constructed and arranged to cause the action of the respective discharging devices at different intervals after engagement.

4. In a composing mechanism, the combination of a magazine, the conveyer-belt parallel therewith, the finger-keys, means for discharging the matrices from the magazine, and an intermediate mechanism controlling the interval of time between the operation of a key and the operation of the corresponding discharging device and giving a greater interval for those devices which are near the point of assemblage than for those which are remote therefrom.

In testimony whereof I hereunto set my hand, this 30th day of March, 1900, in the presence of two attesting witnesses.

JOHN H. LYNCH.
